STEREOTYPE PLATE CASTING BOX

Frank A. Foster, Melrose Park, Ill., assignor to
The Goss Printing Press Company, Chicago,
Ill., a corporation of Illinois

Application May 17, 1946, Serial No. 670,482

5 Claims. (Cl. 22—2)

1

The invention pertains to boxes or machines for casting stereotype plates and has for its general aim the provision of such a mechanism, including a novel and improved arrangement for holding a mat in position within the same by a vacuum.

More particularly, it is an object of the invention to provide such a casting box comprising a complementary pair of hollow shells hinged together to open for removal of the finished casting as well as the mat, and embodying a novel arrangement for equalizing the pressure between vacuum chambers in both of the shells constantly and irrespective of their position relative to each other. By providing for constant inter-communication between such chambers the problem of sealing, such as would be entailed if inter-communication were established between abutting portions of the shells only when they are closed, is obviated. Moreover, the difficulties and unsightliness of utilizing flexible hoses connecting separate ones of the chambers to a vacuum pump are also obviated.

Further objects and advantages of the invention will become apparent as the following description proceeds, taken in connection with the accompanying drawings in which:

Figure 1 is a side elevation of a stereotype plate casting machine embodying the present invention.

Fig. 2 is an end elevation of the machine shown in Fig. 1.

Fig. 3 is a transverse sectional view taken substantially along the line 3—3 in Fig. 2.

Fig. 4 is an enlarged detail sectional view taken substantially along the line 4—4 in Fig. 3.

Fig. 5 is an enlarged detail view of a fragment of the inner face of one of the casting machine shells.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the exemplary embodiment of the invention illustrated in the drawings, the casting box there shown is generally cylindrical in shape and comprises a complementary pair of shells 10, 11 presenting respective semi-cylindrical interior faces 10a, 11a (see Fig.

2

3). The shell 10 is rigidly fixed to a supporting structure comprising uprights 12 rising from a base plate 13. The other shell 11 is hinged to the stationary shell 10 in a manner hereinafter detailed, to swing outwardly into open position, a handle 14 being provided on the movable shell 11 for use in swinging it between open and closed position.

Any suitable means may be provided for locking the shells 10, 11 in closed position. In the present instance a locking lever 15 (Figs. 1 and 2) is pivoted at 16 on the stationary shell 10. Rigid with the lever 15 is a portion or plate 17 having upon its inner face a cam groove 18 arranged to receive a roller 19 so that, as the lever 15 is swung, the movement of the roller along the cam groove forces the movable shell 11 tightly into closed position. The flat edge portions 10b, 11b and 19c of the shells 10, 11 (see Fig. 3) are thus forced solidly into abutment.

Within the enclosure formed by the complementary shells 10, 11 is a core 20 (Fig. 3) which may be constructed and mounted in any suitable manner as, for example, detailed in my Patent No. 2,100,003, issued November 23, 1937. In the latter patent is shown an arrangement for rocking the core outwardly after the movable casting box shell is swung open. In the present instance, the actuating lever 21 is provided for rocking the core but its connections to the core have been omitted in the drawings in the present case for the sake of simplicity and since they form no part of the present invention.

In the normal use of the casting machine here shown, a mat M (Fig. 3) is received against the inner faces 10a, 11a of the casting box shells and type metal is poured into the annular space between the mat and core. To hold the mat firmly and in smooth condition against the inner shell faces 10a, 11a, a plurality of small suction ports 22 (Figs. 3 and 5) is distributed substantially uniformly over such inner faces and vacuum is applied to these ports. The mat is thus sucked against the smooth inner faces of the shells, being held taut and without wrinkling or bulging.

The ports 22 lead from the inner faces of the casting box shells to vacuum chambers 23. The shells are generally hollow in construction to define the chambers 23 and have suitable internal webbing 24 for reinforcement purposes. It will be appreciated that all of the chambers 23 in each shell communicate with each other through suitable openings in the webs but are otherwise closed.

In accordance with the present invention pro-

vision has been made for maintaining continuously an equalization of pressure between the vacuum chambers 23 in both the stationary and movable shells 10 and 11. For that purpose inter-communication is established between the chambers of the two shells through a specially constructed hinge mechanism that joins them. In the illustrative embodiment such hinge mechanism comprises a pintle 25 engaged by interleaved gudgeons 26 integral with respective ones of the shells 10, 11. The pintle 25 may have a pressed fit in the gudgeons 26 of the movable shell 11 and is journaled for rotation in the gudgeons of the stationary shell 10.

The lower portion of the pintle 25 is drilled axially to form a longitudinally extending passage 27 as shown in Fig. 4. Transversely extending passages or ports 28 open from this passage 27 into passages 29 within respective ones of the gudgeons 26. Such passages 29 lead into adjacent ones of the vacuum chambers 23 in the shells 10, 11 (see Fig. 3, as well as Fig. 4).

Special provision is made for sealing the lower gudgeon 26 on the stationary shell 10 with respect to the pintle 25 in view of the fact that this gudgeon is journaled for turning movement on the pintle. It will be observed, in passing, that only the lowermost gudgeons on each of the two shells are concerned in the inter-communicating passage arrangement between the vacuum chambers and accordingly similar sealing is not required for any of the other gudgeons on the shell 10. In the present instance the sealing arrangement includes a sleeve 30 received in an enlarged portion of the bore in the lower gudgeon 26 and telescoped over the pintle 25. Sealing gaskets 31, 32 are located at opposite ends of this sleeve and a stuffing box 33 is telescoped over the lower end of the pintle. Screws 34 secure the stuffing box to the lower gudgeon 26 and, as these screws are tightened, the stuffing box is advanced, compressing both the gaskets 31 and 32, so that these gaskets fully and effectually seal the space between the gudgeon and pintle on opposite sides of the passage 29 to prevent entrance of atmospheric air into the latter passage.

To retain communication between the lower pair of ports 28 in the pintle and the passage 29, an annular relief 35 is provided in the sleeve 30 and ports 36 are drilled in the sleeve to lead into the annular space thus defined. A connection by way of a single conduit or passage may be established from any selected point in the inter-communicating series of passages and chambers in the casting box to a suitable vacuum pump, here indicated generally at 37, and including a built-in electric drive motor. Preferably this connection is made to the passage 27 in the pintle 25 so as to equalize, both in length and general resistance to passage of air, the paths to the pump from the vacuum chambers within respective ones of the shells 10 and 11. Accordingly, a connection to the vacuum pump 37 may be established through a conduit 38 connected to the lower end of the pintle passage 27.

Starting and stopping of the electric drive motor in the vacuum pump unit 37 may, if desired, be controlled automatically in response to opening and closing of the casting box. For that purpose, a normally open micro-switch 40 (Fig. 1) having an operating button 41 is mounted on the lower portion of the stationary shell 10. Co-acting with this switch is a lug or dog 42 fixed to the movable shell 11. When the latter shell is closed, the dog 42 presses in the button 41, closing

the switch 40 to start the motor. Similarly, when the shell 11 is swung to open position, the dog 42 leaves the button 41, permitting the switch 40 to open and thus stop the motor.

I claim as my invention:

1. A casting box for stereotype plates comprising, in combination, a complemental pair of hollow shells presenting generally semi-cylindrical inner faces adapted to receive a mat, each of said shells having a vacuum chamber therein from which lead suction ports opening into the inner face of the shell, a pintle having an axially extending passage therein, gudgeons rigid with respective ones of said shells and engaging said pintle to hinge said shells for opening and closing movement relative to each other, means including passages in said gudgeons for establishing pressure equalizing intercommunication between said vacuum chambers through such passages and through said passage in said pintle, and means for establishing a connection from said interconnected chambers to a vacuum pump.

2. A casting box for stereotype plates comprising, in combination, a cylindrical structure split longitudinally into a complemental pair of semi-cylindrical shells, each shell having a vacuum chamber within it and each of said shells having suction ports therein opening into the inner face of the shell from the corresponding vacuum chamber, a pintle having an axially extending passage therein, gudgeons rigid with adjacent side edge portions of respective ones of said shells and engaging said pintle to hinge said shells for opening and closing movement relative to each other, means including passages in said gudgeons for establishing pressure equalizing intercommunication between said vacuum chambers through such passages and through said passage in said pintle, and means for establishing a connection from said interconnected chambers to a vacuum pump.

3. A casting box for stereotype plates comprising, in combination, a complemental pair of hollow shells presenting generally semi-cylindrical inner faces adapted to receive a mat, each of said shells having a vacuum chamber therein from which lead suction ports opening into the inner face of the shell, a pintle having an axially extending passage therein leading from one end of the same, gudgeons rigid with respective ones of said shells and engaging said pintle to hinge said shells for opening and closing movement relative to each other, one of said gudgeons being freely journaled on said pintle and the other fixed thereon, means including passages in said gudgeons for establishing pressure equalizing intercommunication between said vacuum chambers through such passages and through said passage in said pintle, means for establishing a connection from said interconnected chambers to a vacuum pump, said one gudgeon having an enlarged bore therein, a sleeve in the latter bore telescoped over said pintle and having ports therein through which communication is established to the passage in said one gudgeon to the passage in said pintle, sealing gaskets at each end of said sleeve, and a stuffing box for compressing said gaskets.

4. A casting box for stereotype plates comprising, in combination, a cylindrical structure split longitudinally into first and second semi-cylindrical shells, each shell having a vacuum chamber within it and each of said shells having suction ports therein opening into the inner face of the shell from the corresponding vacuum chamber.

ber, a pintle having an axially extending passage therein and including means for connecting the same to a vacuum pump, interfitting gudgeons rigid with adjacent side portions of respective ones of said shells and engaging said pintle to hinge said shells for opening and closing movement relative to each other, means including a port for connecting said passage through a gudgeon of said first shell to the vacuum chamber therein, one of said gudgeons on said second shell being 10 hollowed out to form a recess in communication with the associated vacuum chamber and penetrated by said pintle, said pintle having ports formed therein to provide communication between said passage and said recess, and sealing means radially arranged about said pintle and in sealing engagement with the gudgeon on said second shell for insuring that said recess is sealed against entry of outside air even under conditions of non-sealing engagement between the opposed surfaces on adjacent gudgeons.

5. A casting box for stereotype plates comprising, in combination, a complemental pair of hollow shells presenting generally semi-cylindrical inner faces adapted to receive a mat, each of said shells having a vacuum chamber therein from which lead suction ports opening into the inner

face of the shell, a pintle having an axially extending passage therein for connection to a vacuum pump, interfitting gudgeons rigid with respective ones of said shells and engaging said pintle to hinge said shells for opening and closing movement relative to each other, and means including passages in said gudgeons for establishing a pressure equalizing intercommunication between said vacuum chambers through said passages and through said passage in said pintle, and sealing means in at least one of said gudgeons and radially arranged about said pintle for sealing the same against entry of outside air independently of the interfitting faces on said 15 gudgeons.
